UNITED STATES PATENT OFFICE

FELIX K. ALSTRAND, OF NEW YORK, N. Y.

GARMENT FASTENER

Application filed July 8, 1929. Serial No. 376,788.

This invention relates to garment fasteners which are adapted to be used in connection with the button holes or punched holes in a garment, and pertains more particularly to that class of fasteners in which a wire or strip of metal or other suitable material is bent to form a relatively flat base having one or more loops projecting intermediately therefrom through the mentioned holes in the garment, said base being preferably covered by fabric or other coating to conceal the wire therein.

The main object and feature of my invention is to provide a fastener of the character indicated which is readily made from a piece of wire or metal strip and which may be sewed in place upon one portion of a garment so as to prevent loss thereof and bring out the advantages of the fastener to the utmost and also render the same permanently useful.

Another feature is to make such a fastener free from hinged joints or loose members, and which may instead be bent over the edges of a button hole and have the advantages of fasteners otherwise made of several parts.

A further feature is to form a strip or wire symmetrically into a fastener so that it partakes of the symmetrical features of a button, the base of the fastener being also made to resemble the base of a button when desired by covering the same with pads of fabric or coating it with rubber, celluloid or any other material that suggests itself for such purpose.

Other features and the various advantages of my invention will appear more in detail as this specification proceeds.

40 In the accompanying drawings forming part hereof:—

Fig. 1 is a view of one form of my fastener which is provided with two loops, being also shown without any covering for the base thereof.

Fig. 2 is a view of a garment with the fastener applied to one of a pair of corresponding portions of said garment and preferably sewed thereon.

50 Fig. 3 is a similar view with the fastener

also passed into the button hole of the second garment portion.

Fig. 4 is another view of the same garment portions with the loops of the fastener bent down in final effective position to hold 55 the garment portions in assembled relation.

Fig. 5 illustrates the fastener when covered upon its base with a pair of fabric pads to conceal the wire in the base.

Fig. 6 is a simpler form of the same fastener, shown as in Fig. 1 without any base covering, but having here only one loop.

Fig. 7 shows the same simplified form with a covered base as in Fig. 5.

Fig. 8 demonstrates the preferred manner of applying the same fastener to one portion of the garment before shown.

Fig. 9 is a front view of the same garment portion and reveals the projecting loop of the fastener.

Fig. 10 shows the garment with its corresponding portions held in assembled relation by means of the loop of the fastener which is bent horizontally down upon the garment.

Throughout the views the same reference numerals indicate the same or duplicate parts.

It is a common fault of collar buttons and the like that they are rigid and press upon the throat or neck in an uncomfortable manner, are easily dropped and lost, and in the case of buttons made of two or more parts, the same become worn or maladjusted so that they cease to function properly. It is herein proposed to eliminate these troubles by having a fastener which in some respects resembles a button, which is fastened to the garment, and which has the advantages of two or three parts fasteners without any of their disadvantages due to wear and tear.

In the practice of my invention, a piece of metal strip or wire, for example, of tinned iron, silvered copper or the like may be bent into a general form as indicated at 1, where a pair of enveloping branches or arms 2, 2 form the outline of a base lying in substantially the same plane and terminate at their outer extremities in the curved ends 3, 3. The intermediate parts of the wire are formed into a pair of similar upright loops 5, 5 having 100

a low intermediate portion 6 lying between them in the same general plane of the base formed by the branches 2, 2, while the latter connect with the loops by means of the short outer sections 4, 4 which are both in the general plane of the base. These portions 4, 4 are not essential, as the loops can be spread out enough, or a third loop can be added so that they connect directly with the branches 5 2, 2, or the latter can be drawn inward to meet the loops.

On the other hand, the fastener can have but one loop as generally indicated at 17 in Fig. 6, the arms or branches being here noted 15 18, 18, terminating in ends 19, 19, and brought in at their other ends to form connecting members 20, 20 which are continuous with the intermediate loop 21 which they carry.

If the fastener 1 is again considered, the 20 same may be applied to a garment instead of a button or other fastener, the loops 5, 5 being then passed through a pair of holes punched for them or through an ordinary button hole. In Fig. 2 this fastener is thus placed in position in the neck band end 7 of garment portion 25 8 so that the base formed by the parts 2, 2, 3, 3, 4, 4, and 6 are behind the neck band portion 7 and the loops 5, 5 pass through the same at the normal front button position, the 30 fastener being then preferably sewed in place. When secured in this position, one way of concealing the wire portions forming the base is indicated in Figs. 2 and 3 where a covering flap 12 is arranged to be sewed over the base 35 wires. If the fastener 17 were secured to the garment, it could be similarly treated and its base wires thus covered, if desired.

However, the loops 5, 5 may now be passed by a user through the button hole 11 in neck 40 band member 9 of the garment portion 10 as indicated in Fig. 3, and if so desired, a collar may be added and the loops also passed through the button holes thereof as through 45 11. Another fastener may then also be used for the rear of the neck band and collar, say 50 for example the fastener form 17. In this case, the final operation in using the fastener 1 is performed by bending up one loop and bending down the other, presenting the appearance indicated in Fig. 4. The loops in 55 this relation lie rather flat and are unobtrusive, and hold the garment portions securely in assembled relation. In order to again release the garment members, it is obviously but necessary to bend back or straighten the loops 60 into their projecting position as at first, when they will no longer hold the garment members by the button holes and they may readily be drawn apart.

60 On the other hand, if the fastener form has one loop as at 17, the same may be passed through a smaller hole 23, unless a button hole already exists in garment member 8 in the neck band portion 7, and when the neck band 65 portion 9 is placed over part 7 and the loop

there passed through another small hole 24 unless a regular button hole like 11 is already made in the member. The loop 21 may be bent horizontally against the neck band portion 9 and will hold the garment members assembled as before in the case of loops 5, 5. The main principle is the same in both cases, or even where three or four loops would be used.

In order to enhance the appearance and utility of the fastener generally, I prefer also to cover the base with fabric, rubber, celluloid or composition. In the case of branches 2, 2 or of branches 18, 18, a flat pad of such material at 13 may be placed under them and the edge turned over the wire branches and then an upper piece of similar material 14 laid over the other and the two united. In the case of fabric, it would possibly be sewed to the bottom pad at 15, while in the case of rubber or other composition, pressure, heat or exposure to air would accomplish the union of the whole into a serviceable unit.

Having now fully described my invention, I claim:

1. A garment fastener formed of wire or strip including a base portion arranged to be secured to one of a pair of corresponding garment members, and a plurality of loops projecting intermediately from said base portion and arranged to project through said other garment member and be bent in different directions over the same in order to hold said garment members in secure assembled relation.

2. A garment fastener including a wire bent to form a pair of enveloping branches lying in the same plane generally, a plurality of loops initially bent upward from said branches in substantial alinement, and intermediate connecting wire links directly connecting each pair of adjacent loops and also arranged in substantially the same general plane of said branches, said loops being arranged to be simultaneously passed through button holes in garments and bent independently into individual directions to provide a retaining effect subsequent to the introduction of said loops in their initial condition.

3. A garment fastener including a wire or strip bent at both ends to form a fastener base arranged in one general plane, and a loop directly connected intermediately to said base and initially bent upright from the same, said loop being adapted to be passed through a button hole in a garment and thereafter bent over to provide a retaining effect.

4. A garment fastener including a wire or strip bent at both ends to form a fastener base arranged in one general plane, a loop directly connected intermediately to said base and initially bent upright from the same, said loop being adapted to be passed through a button hole in a garment and subsequently

bent over to produce a retaining effect, and means to cover and conceal said base.

5. A garment fastener formed of wire or strip including one or more loops which are arranged upright upon a base formed of the ends of said wire or strip, said ends being bent about the same general axis in the same rotative direction but upon opposite sides of said fastener, said one or more loops being 10 arranged to be bent down upon said base during use, and a covering for said base to conceal said wire ends while exposing said one or more loops for manipulation and use as retaining means.

15. 6. A garment fastener formed of a wire or strip whose ends are bent into a pair of enveloping branches so as to constitute a base adapted to be secured to one of a pair of corresponding garment members, a loop directly integral with said branches and projecting initially in a substantially upright position therefrom, said loop being arranged 20 to be passed through a button hole in the second of said garment members and subsequently bent over the same in order to provide 25 a retaining effect.

7. A garment fastener formed of wire or strip including a substantially plane base portion, and an upright intermediate member secured directly upon said base portion and adapted to be passed through a garment member and thereafter bent over the same to provide a retaining effect.

FELIX K. ALSTRAND.
